ROBERT E. BLOOM, OF BROOKLYN, NEW YORK.

DUST-CAP FOR VALVE-STEMS.

1,330,577.

Specification of Letters Patent. Patented Feb. 10, 1920.

Application filed May 20, 1919. Serial No. 298,352.

To all whom it may concern:

Be it known that I, ROBERT E. BLOOM, of Brooklyn, in the county of Kings and State of New York, have invented certain new 5 and useful Improvements in Dust-Caps for Valve-Stems; and I do hereby declare the following to be a full, clear, and exact description of the invention, such as will enable others skilled in the art to which it 10 appertains to make and use the same.

My invention relates to dust caps for valve stems of pneumatic tires, being particularly adapted for use in connection with automobile tires, and the object of the invention is to provide a simple cap for this purpose embodying improved means for retaining the cap on the valve stem and which will permit a quick placing or removal of the cap without the necessity of laboriously 20 turning the cap as where screw threaded engagement is had between the parts.

In the drawing, Figure 1 is a vertical sectional view showing my improved cap applied to the valve stem. Fig. 2 is a view 25 in perspective showing the clamping elements detached from the cap.

The valve stem A which is of known form with screw threads extending throughout its length projects inwardly through an opening 30 in the wheel rim and is made fast to the rim by a nut B.

My improved cap 1 is of tubular form, closed at its upper end, and at a point adjacent its lower end is bulged, as at 2, a part 35 of this bulged portion being cut away to form an opening 3 for a clamp which comprises complementary levers 4 and 5 extending transversely of the cap. Each of these levers is formed of a flat piece of metal with 40 angularly disposed ears 6 by which it is pivotally secured to the bulged portion 2 of the cap, at a point removed from the longitudinal center of the cap, through the instrumentality of a pin 7 the pin forming a bearing 45 for a coiled spring 8 adapted to exert tension on the levers.

That portion of each lever wholly within the bulged part 2 of the cap is ring-like in form, the opening being of a diameter 50 slightly larger than that of the valve stem so that in one position of the lever it will freely pass over the threads of the stem while in its opposite position it will engage the screw threads and prevent the cap from 55 being jostled or otherwise removed from the stem. The two levers are in spaced relation

to each other this being effected by having the ears 6 of the lever 4 extending downwardly and those of the lever 5 upwardly, the pin 7 being common to both levers. The 60 ends of the spring 8 respectively bear against the outer ends of the levers and tend to force these ends apart and the ring-like portions toward each other and into engagement with the threads. In applying 65 or removing the cap the outer ends of the levers are pressed so that the inner ends will practically be in parallelism and free to slip over the threads. Too great compression would cause the inner ends of the 70 levers to pass beyond a point where the cap could readily be slipped off the stem, and to prevent any chance of this I provide the lever 5 with a stop 9 which is formed by bending the end of the lever upwardly so 75 that it will lie directly under the end of the lever 4 and when both are compressed they cannot move beyond the point which will allow the inner ends to freely slide over the valve stem.

To insure against the cap vibrating relatively to the stem I provide rubber gaskets 80 12 and 13 fitted, respectively, near the top and bottom of the cap, the gasket 12 having a small orifice to receive the small valve 85 cap while the gasket 13 must be of sufficient size to permit passage of the valve stem. It will be noticed that any pull on the cap, without first compressing the outer ends of the levers, will have a tendency to make the 90 levers bite the screws of the stem with greater force.

I claim as my invention:

1. In combination with a valve stem having an external thread, a dust cap of 95 tubular form having a circumferential bulged portion terminating in an opening at one side, and including clamping means secured to said cap, said clamping means having a portion fitting within the bulged 100 part of the cap and adapted to encircle and engage the threaded stem.

2. In combination with a valve stem having an external thread, a dust cap of tubular form having an opening at one side, 105 and including spaced apart clamping levers pivoted to said cap, said levers each having a portion extending through said opening and into engagement with said threaded stem, and a spring for forcing the thread 110 engaging ends of said levers toward each other.

3. In combination with a valve stem having an external thread, a dust cap of tubular form having an opening at one side, and including spaced apart clamping levers fitted to said cap, each of said levers having a ring-like portion adapted to surround the valve stem, and a spring normally tending to force the ring-like portions of said levers into engagement with the threads of said stem to lock the cap thereto.
4. In combination with a valve stem having an external thread, a dust cap of tubular form having an opening at one side, and including spaced apart clamping levers fitted to said cap, each of said levers having a ring-like portion adapted to surround the valve stem, and a spring normally tending to force the ring-like portions of said levers toward each other and into engagement with the threads of said stem to lock the cap thereto, and a stop carried by one of said levers to limit movement of said levers against the tension of said spring.

In testimony whereof I have signed this specification.

ROBERT E. BLOOM.
